Primary Examiner — Omeed Agilee(74) *Attorney, Agent, or Firm* — Nancy J. Flint, Attorney At Law, P.A.; Nancy J. Flint, Esq.(57) **CLAIM**

The ornamental design for a specimen bottle, as shown and described.

DESCRIPTION

FIG. 1 is a perspective view of a first embodiment of a specimen bottle showing my new design;

FIG. 2 is an exploded perspective view thereof;

FIG. 3 is a top view of the specimen bottle in an assembled configuration;

FIG. 4 is a front view thereof;

FIG. 5 is a cross-sectional view thereof taken along line 5-5 in FIG. 3;

FIG. 6 is a bottom view thereof;

FIG. 7 is a perspective view of a second embodiment of a specimen bottle;

FIG. 8 is an exploded perspective view thereof;

FIG. 9 is a top view of the specimen bottle in an assembled configuration;

FIG. 10 is a front view thereof;

FIG. 11 is a cross-sectional view thereof taken along line 11-11 in FIG. 9; and,

FIG. 12 is a bottom view thereof.
